PERFORATING DEVICE

Harry D. Snyder, New York, and Emil Kern,
Flushing, N. Y.

Application January 29, 1934, Serial No. 708,725

8 Claims. (Cl. 164—91)

This invention relates to punches or perforating devices adapted particularly for perforating sheets to facilitate binding thereof with fasteners or like means in files or binders.

5 It is the object of the invention to provide a sturdy and efficient but relatively inexpensive perforating device embodying a number of practical improvements, and especially a device the principal parts of which may be constructed of 10 sheet metal.

Other objects and advantages of the invention will be apparent as it is better understood by reference to the following specification and the accompanying drawing, in which

15 Fig. 1 is a plan view of the perforating device; Fig. 2 is an enlarged sectional view on the line 2—2 of Fig. 1; Fig. 3 is a section on the line 3—3 of Fig. 2; Fig. 4 is a section on the line 4—4 of Fig. 2; and 20 Fig. 5 is a view in perspective of one of the punch guide standards.

Referring to the drawing, 5 indicates a base which may be made of any suitable sheet metal such as steel, the lateral edges 6 being bent to 25 afford a raised support. The front of the base may be closed by a strip 7 of metal secured by rivets 8 or otherwise to the lateral edges 6.

Upon the base 5, two or more standards 9 may be secured by rivets 10 or otherwise to a raised 30 table 11. These standards are constructed of any suitable sheet metal, preferably steel, as more clearly illustrated in Fig. 5, in which it will be noted that the sheet metal is bent to generally 35 rectangular form, providing bottom and top members 12 and 13 and sides 14 with projecting ears 15. The bottom 12 and top 13 are provided with oppositely disposed openings 16 and 17 to receive and guide the punch 18. To assure proper 40 alignment of the punch and to prevent escape of the lower end thereof from the opening in the bottom 12, an upwardly projecting boss 19 is formed from the body of the metal. Thus the 45 two openings afford a rigid guide permitting vertical movement of the punch 18.

An operating handle 20 is provided with 45 branches 21 and connected by pins 22 to the punches 18. Springs 23, resting on the tops 13 of the standards 9, engage the pins 22 and normally hold the punches 18 in their uppermost 50 position. The branches 21 of the handle 20 carry pins 24 which engage slots 25 in the ears 15 of the standards 9. The axes of the slots 25 are disposed at an angle to the horizontal plane, and the pins 24 are adapted to ride downwardly in 55 the slots as the handle 20 is depressed. Thus the

pivotal center shifts with the movement of the handle, and the punches 18 are permitted to move vertically without binding in the guides.

The base 5 is provided with openings or dies 26 beneath the punches 18 and co-operating therewith when the handle 20 is depressed. Consequently, when one or more sheets are introduced beneath the punches they may be perforated by the depression of the handle 20. The bits of sheet material thus removed are delivered 10 to a tray 27 consisting of sheet metal having an upturned lip 28 at one end and a similar lip 29 at the opposite end. The bottom of the tray 27 travels in grooves 30 of the edges, thus forming a part of the base, and consequently the tray 15 may be moved in and out to receive and deliver the punchings. The upturned edge 28 is sufficiently high to cause it to bind slightly under the base 5 when it is moved to its innermost position. A projection 31 enables the user to release the 20 tray by pulling it outwardly when desired.

The lip 29 is disposed at an angle so that the bits of sheet material or punchings are caused to slide rearwardly as they are delivered to the tray. This device obviates a difficulty heretofore experienced in which the punchings pile up under the punches and tend to jam the device instead of spreading through the tray. With the angularly disposed lip, the punchings slide rearwardly into the tray and are distributed as they 30 accumulate, until the tray is substantially filled.

To facilitate the handling of sheet material and the spacing of the perforations therein, an embossed indicator 32 is provided on the surface of the base 5. There is also a depression 33 in 35 the surface of the base 5 to afford a support for a guide 34 which is preferably split at 35 to afford a friction engagement. A projection 36 at the end of the guide provides a limit for the edge of the sheet material. Obviously, the guide 40 may be shifted in the base and set at any desired position, so that consecutive sheets of material 45 may be punched with the perforations at the desired distance from the edge.

The perforating device as described, with the exception of the punches and springs and the necessary pins, is made from sheet metal stamped or otherwise formed in the desired shape. The required operations, as well as the material used, 50 are relatively inexpensive, and the punch may be manufactured at a much lower cost than has been possible heretofore. Furthermore, the structure is particularly sturdy. It will withstand rough and continued usage over long periods, 55

and it embodies numerous advantageous features hereinbefore described.

Various changes may be made in the details of construction and arrangement of the parts 5 without departing from the invention or sacrificing any of the advantages thereof.

We claim:

1. A perforating device comprising a base, standards thereon each of sheet metal bent to 10 provide a top and bottom with guide openings therein and projecting ears, punches supported in the guide openings and an operating lever pivotally connected to the punches and fulcrumed in slots formed in the ears, the slots being disposed with their axes in angular relation to a horizontal plane parallel to the base.

2. A perforating device comprising a base, standards thereon each of sheet metal bent to 20 provide a top and bottom with guide openings therein and projecting ears, a boss formed from the body of the metal and surrounding each bottom guide opening, punches supported in the 25 guide openings and an operating lever pivotally connected to the punches and fulcrumed in slots formed in the ears, the slots being disposed with their axes in angular relation to a horizontal plane parallel to the base.

3. In a perforating device, a standard adapted to support a punch and consisting of sheet metal 30 bent to provide a top and bottom with guide openings therein, and projecting ears having slots therein disposed with their axes in angular relation to a horizontal plane parallel to the bottom of the standard.

35 4. A perforating device comprising a base, standards thereon each of sheet metal bent to provide a top and a bottom with guide openings therein, a pair of projecting ears extending upwardly from each of said standards, a fulcrum pin 40 journaled in each pair of ears, punches supported in the guide openings, and an operating lever connected to the punches and fulcrumed on said pins.

5. A perforating device comprising a base, standards thereon each of sheet metal bent to provide a top and a bottom with guide openings therein, a pair of ears projecting upwardly from each of said standards and each provided with an elongated slot, a fulcrum pin journaled in each pair of ears and positioned in said slots, punches supported in the guide openings, and an operating lever pivotally connected to the punches and fulcrumed on said pins. 5

6. A perforating device comprising a base, standards thereon each of sheet metal bent to provide a top and a bottom with guide openings therein, a pair of ears projecting upwardly from each of said standards and having elongated slots formed therein, a fulcrum pin journaled in said ears and positioned in said slots, a boss formed from the body of the metal of the standards and surrounding each bottom guide opening, punches supported in the guide openings, and a lever fulcrumed on said pins for operating said punches. 10 15

7. A perforating device comprising a base, a standard thereon of sheet metal bent to provide a top and a bottom with guide openings 25 therein, a pair of ears projecting upwardly from said standard and having elongated slots therein, a fulcrum pin journaled in said ears and positioned in said slots, a punch supported in the guide openings, and a lever fulcrumed on said 30 pin for operating said punch.

8. A perforating device comprising a base, a standard thereon of sheet metal bent to provide a top and a bottom with guide openings therein, a pair of ears projecting from said standard and having elongated slots formed therein, a fulcrum pin journaled in said ears and positioned in said slots, punches supported in the 35 guide openings, and an operating lever pivotally connected to the punches and fulcrumed on said pins. 40
